UNITED STATES PATENT OFFICE.

JOHN A. JOBSON, OF SHAMOKIN, PENNSYLVANIA.

AMUSEMENT APPARATUS.

1,109,421.

Specification of Letters Patent.

Patented Sept. 1, 1914.

Application filed December 30, 1913. Serial No. 809,512.

To all whom it may concern:

Be it known that I, JOHN A. JOBSON, a citizen of the United States, residing at Shamokin, in the county of Northumberland and State of Pennsylvania, have invented certain new and useful Improvements in Amusement Apparatus, of which the following is a specification.

My invention relates to improvements in amusement apparatus ordinarily known as "merry-go-rounds."

An important object of the invention is to provide apparatus of the above mentioned character, which is so constructed that the same is highly safe in use, the operating elements or parts thereof being arranged under cover for preventing the passengers coming in contact with the same.

A further object of the invention is to provide apparatus of the above mentioned character, which is of simple construction, strong, easy to operate, and comparatively inexpensive to manufacture.

A further object of the invention is to provide apparatus of the above mentioned character, which will be particularly attractive to persons, both young and old.

Other objects and advantages of this invention will be apparent during the course of the following description.

In the accompanying drawings, forming a part of this specification and in which like numerals are employed to designate like parts throughout the same, Figure 1 is a plan view of a complete apparatus embodying my invention. Fig. 2 is a central longitudinal sectional view therethrough. Fig. 3 is an enlarged sectional view through a portion of the apparatus. Fig. 4 is a detail plan view of attaching means embodied in the invention. Fig. 5 is a fragmentary plan view of an operating ring, showing means attached thereto for preventing the removal of a coupling element. Fig. 6 is a fragmentary perspective view of a portion of a track, the elements thereof being separated. Fig. 7 is an enlarged transverse sectional view through the rotating ring, showing in elevation, means for holding a bolt against rotation.

In the drawings, wherein for the purpose of illustration is shown a preferred embodiment of my invention, the numeral 10 designates a relatively stationary base or foundation as a whole, which is preferably formed of concrete or other plastic material.

This foundation preferably includes spaced concentric rings 11, 12, 13 and 14, which are connected by horizontal rings or annular supports 15, 16 and 17. The relatively stationary rings or annular supports 15 and 16 are preferably provided with annular recesses 18, receiving therein rotatable annular platforms or supports 19, which are identical. Each of the annular supports or platforms 19 is provided upon its lower surface with annular grooves, receiving annular track-casings 20 (see Figs. 3 and 6), which are substantially semi-circular in cross-section and preferably arranged in pairs, as shown. These annular track-casings are rigidly attached to the annular supports or platforms 19 by any suitable means. Arranged below and in registration with the track-casings 20 are similar track-casings 21, which are annular and formed substantially semi-circular in cross-section. These track-casings 21 are embedded within the relatively stationary rings or annular supports 15, as shown. The track-casings 21 are rigidly attached to the supports 15 by any suitable means. When assembled, the track-casings 20 and 21, form closed tubular annular track-casings, within which are freely rotatably mounted bearing-balls 22, as shown.

In the ordinary "merry-go-round" construction, it has generally been customary to provide a central pole or mast, to which the revoluble part or parts of the apparatus were attached, for preventing them from being displaced, due to the action of centrifugal force. This construction has been found to be clumsy and expensive and has failed to operate wholly satisfactorily. Particular attention is called to the fact that in my construction the central post or mast is dispensed with, and at the same time means are provided which positively hold the revoluble parts of the apparatus against displacement, with the least friction, such means being embodied in the track-casing 20 and 21 and bearing-balls contained therein. While it is not essential, I may interpose bearing-balls 22a, between platforms 19 and walls of the annular recess 18, as shown. As more clearly shown in Figs. 2 and 3, each of the rotatable platforms or supports 19 is provided with a depending annular flange 23, operating within an annular slot 24, as shown. Attached to the depending annular flange 23 is an annular rack-bar 25, embody-

ing bevel gear teeth, engaged by bevel gears 26, rigidly mounted upon horizontal stub-shafts 27, preferably diametrically oppositely arranged, as shown. Each stub-shaft 27 is provided with a sprocket wheel 28, rigidly mounted thereon, engaged by a sprocket chain 29, engaging a sprocket wheel 30. Each sprocket wheel 30 is driven by a rotatable horizontal drive shaft 31. As clearly shown in Fig. 2, the drive shafts 31 are diametrically oppositely arranged.

The drive shafts 31 have bevel gears 32 rigidly connected with their inner ends, engaging with and driven by a common bevel gear 33, which is driven by a motor 34, which in the present instance is shown as an internal combustion engine, while a steam engine, electric motor, or any other source of power may be advantageously employed.

In this connection particular attention is called to the fact that the motor 34 is arranged within the innermost ring 11, the drive shafts 31 and associated elements being all arranged wholly below the relatively stationary supports or rings 15, 16 and 17, whereby such driving or operating elements are always under cover thus preventing the passengers from coming in contact therewith, and a highly safe apparatus is obtained. The space within the ring 11 may preferably be closed by a cover or top 35, having a door 36, adjacent which is arranged steps 37, whereby the operator may have proper access to the engine or motor.

Arranged upon the outermost relatively stationary annular support or ring 17 is a relatively stationary annular support or platform 38, attached thereto by any suitable means, the same being mounted within an annular recess 30' and held thereby against perceptible lateral movement.

Mounted to travel upon the relatively stationary annular support or platform 38 are a suitable number of automobiles 39 which may be of any well known or preferred type, except that their inner wheels 40 are constructed slightly smaller than the outer wheels, to compensate in the difference of distance that the inner and outer sets of wheels have to travel. The bodies of the automobiles are horizontal. The stationary annular support or ring 17 is provided with an annular slot 42, receiving upstanding coupling elements 43 in the form of bolts.

I preferably employ two of these bolts for each automobile, the same being connected with the front and rear axles of the automobile. As clearly shown in Fig. 4, each axle 44' has a strap or hasp 44, hinged thereto as shown at 45, the same having its material between the ends thereof bent outwardly, providing a vertical pocket 46, receiving the upper portion of the bolt 43. At its free end the strap or hasp 44 is apertured 65 to extend into a forked apertured element

47 suitably attached to the axle, such elements being preferably connected by a padlock 48. Other suitable means may be employed for connecting the bolt with the axle. This construction however is particularly advantageous, inasmuch as it prevents the improper disconnection of the bolts from the automobile axles and also enables the same to be quickly disconnected by the proper person. Attention is called to the fact that the automobile is capable of partaking of restricted vertical movements with relation to the bolts 43, as shown in Fig. 2, thus allowing the same to pass over certain obstructions, such as a coat or the like, which not infrequently fall upon the track by accident or carelessness of the passengers in the automobiles. Arranged below the stationary annular platform or support 38 is an operating ring 48, disposed within an annular slot 49. The ring 48 is driven by an annular rack-bar 50, provided with bevel gear teeth, engaged by bevel gears 51, rigidly mounted upon the outer ends of the drive shafts 31, as shown. Particular attention is called to the fact that the operating ring 48 is arranged wholly below the relatively stationary track or support 38, whereby it is impossible for the passengers to come in contact with the operating ring, thus eliminating the possibility of accidents.

The bolts 43, as clearly shown in Fig. 7, pass through openings 52 formed through the operating ring 48. Upon its lower side, this operating ring is provided with recesses 53, receiving nuts 54, and holding them against turning movement. The annular rack-bar 50 engages the nuts and the same is preferably connected with the operating ring 48 by means of screws or bolts. The bolts 43 are turned or screwed up to the desired position, the same having their upper portion 55 formed square in cross-section, whereby such bolts may be held against further turning movement by forked holding elements 56, attached to the ring 48 by means of screws or bolts 57, subsequently to the proper manipulation of the bolts, as above stated. The slot 42 is made sufficiently large to receive the heads of the bolts, whereby the annular platform or support 38 may be placed in its operative position, subsequently to the proper manipulation of the bolts 43.

As above stated the automobiles 39 travel or move longitudinally of the relatively stationary platform or support 38, while the outer rotatable platform or support 19 carries horses 58, stationary with relation thereto. The inner track 19 may be provided with chairs, swings, seats or the like.

In order to produce the effect, that the automobiles are traveling faster than the horses, I have ring 48 geared with the drive shafts 31, so that it will rotate faster than

either of the platforms or supports 19. Attention is called to the fact that the movable and stationary platforms or supports 19 and 38 are arranged in stepped relation, 5 increasing in height inwardly, the exact distance of one step above the other, however, being immaterial.

In the operation of the apparatus, the engine 34 is started, (which should be of 10 a construction that may be readily started and stopped or there may be suitable clutch means for controlling the rotation of the drive shafts 31 by it), whereby the drive shafts 31 are rotated. These drive shafts, 15 through the medium of bevel gears 51, and rack-bar 50, rotate the ring 48, which through the medium of the coupling elements 43 cause the automobiles to travel longitudinally of the relatively stationary 20 platforms or support 38. The rotation of the drive shafts 31 are transmitted to the shafts 27, which drive the rotatable supports of platforms 19. The horses or the like carried by these supports or platforms 25 are bodily rotated therewith.

It is to be understood that the form of my invention herewith shown and described is to be taken as a preferred example of the same, and that various changes in the 30 shape, size and arrangements of parts may be resorted to without departing from the spirit of the invention or the scope of the subjoined claims.

Having described my invention, I 35 claim:—

1. In apparatus of the character described, the combination with a relatively stationary substantially circular support provided with an annular slot, of an automobile mounted to travel upon the relatively stationary support, an operating ring arranged wholly below the relatively stationary support and adjacent the annular slot, coupling means between the automobile and operating ring, and means to drive the operating ring.

2. In apparatus of the character described, the combination with a relatively stationary support provided with a substantially annular slot, of an automobile mounted to travel upon the relatively stationary support, an operating ring arranged wholly below the relatively stationary support adjacent the annular slot, a bolt connected 55 with the axle of the automobile and with the operating ring, means connected with the operating ring for positively preventing the rotation of the bolt with relation thereto, and means to rotate the operating 60 ring.

3. In apparatus of the character described, the combination with a relatively stationary support provided with a substantially annular slot, of a vehicle mounted 65 upon the relatively stationary support to

travel thereon in proximity to the annular slot, an operating ring arranged below the relatively stationary support and adjacent the annular slot, operative connections between the vehicle and operating ring, and 70 means to drive the operating ring, substantially as described.

4. In apparatus of the character described, the combination with a relatively stationary support including a plurality of 75 hollow supporting-members having their upper closed walls provided with substantially annular slots, annular gears arranged within the hollow supporting-members and disposed near the annular slots thereof, vehicles arranged upon the supporting-members, connecting means between the annular gears and the vehicles and passing through the annular slots, a common driving shaft passing through the lower portion of the 80 hollow supporting-members, gearing connecting the common driving shaft with the annular gears, and means to rotate the common driving shaft.

5. In apparatus of the character described, the combination with a relatively stationary support including a plurality of stepped concentric hollow supporting-members having their upper sides closed by 95 walls provided with substantially annular slots, a common driving shaft journaled through the lower portions of the hollow supporting-members, annular gears arranged within the hollow supporting-members adjacent the substantially annular slots 100 thereof, a gear connected with the outer end of the common driving shaft and engaging the annular gear within the outermost hollow supporting-member, shafts arranged above the common driving shaft and journaled within the upper portions of the inner supporting-members, gears carried by the said shafts and engaging the annular gears within the inner supporting-members, driving connecting means between the common driving shaft and said shafts, and 105 means to rotate the common driving shaft.

6. In apparatus of the character described, the combination with a relatively stationary support including a plurality of 115 stepped concentric hollow supporting-members having their upper sides closed by walls provided with substantially annular slots, the innermost hollow supporting-member forming a chamber to receive a motor, 120 of a motor arranged within the chamber, means to cover the chamber, a common driving shaft journaled through the lower portions of the hollow supporting-members, annular gears arranged within the hollow 125 supporting-members adjacent the substantially annular slots thereof, shafts journaled within the upper portions of the hollow supporting-members above the common driving shaft, gears carried by said shafts and en- 130

gaging the annular gears, driving connecting means between the common driving shaft and each of said shafts, vehicles to travel above the supporting-members, means
6 connecting the annular gears with the vehicles, and means connecting the common driving shaft with the motor.

In testimony whereof I affix my signature in presence of two witnesses.

JOHN A. JOBSON.
